CAP FOR TYPEWRITER KEY BARS

Jack Linsky, New York, N. Y.

Application November 11, 1935, Serial No. 49,147

8 Claims. (Cl. 197—103)

The subject matter of this invention is a finger cushioning device applicable for use in connection with typewriter keys. Particularly, however, the invention is concerned with an improved and simplified key cushioning device comprising an annular shell removably mounted on a typewriter key and comprising a relatively soft and resilient cap shaped top retained by an annular flange of the shell.

The invention has as an object the provision of an annular backing retained against downward displacement within the shell and including a plurality of spaced prongs cooperating with an annular depending flange of the cap to lock the latter to the shell and prevent the removal thereof. The invention further comprehends as an object the provision of an anchoring seat in the form of an annular backing non-rotatably sustaining the resilient cap concentrically locked relative to the shell. The invention further contemplates as a further object the provision of an anchoring channeled plate or backing comprising a plurality of spaced upstanding fingers each including relatively sharp and pointed terminals cooperating with an annular flange of the shell to compress the annular depending flange of the cap to prevent removal thereof from the shell.

The invention consists in certain new and original features of construction and combination of parts hereinafter set forth and claimed and as to its other objects and advantages, the mode of operation and manner of its organization, these, inter alia, may be better understood by referring to the following description considered in connection with the accompanying drawing forming a part thereof in which:

Fig. 1 is a vertical side view of a typewriter key with a finger cushioning device according to my invention applied thereto.

Fig. 2 is an enlarged vertical and sectional view of the cushioning device illustrated in Fig. 1, taken on the line 2—2 of Fig. 3.

Fig. 3 is an underneath view of Fig. 2 and

Fig. 4 is an exploded or unassembled view in perspective of the component parts of the finger cushioning device illustrated in the preceding views.

The finger cushioning device according to the invention comprises an annular sleeve or shell 10, a relatively soft rubber indicia carrying cap 11 and an anchoring plate or backing 12. Cap 11 is in the form of a one piece cylindrical member having a top wall 13 from which integrally depends an annular skirt or flange 14. Top wall 13 together with annular flange 14 define a centrally arranged recess or chamber 15. It will be noted that the lower portion of an annular flange 14 is provided with an integrally connected and inwardly disposed annular lip 16, presenting a continuous and inclined surface.

Annular flange 14 embodies an annular and horizontally disposed groove or channel 17 cooperating to snugly receive an inwardly overhanging and downwardly inclined annular flange or rim 18 integral with sleeve 10. The anchoring backing 12 is retained against downward displacement by the inclined and tapering detent 19 bent inwardly from the body of shell 10.

According to the invention, the annular backing or frame 12 includes a horizontal wall 20 having an outer annular upstanding flange 21 and a plurality of spaced prongs 22 each of which comprises an upwardly extending inclined finger 23 having a relatively sharp tapered and pointed outwardly and upwardly extending terminal 24.

Backing 12 may be bent out of sheet metal stock and is a one piece member. This backing is utilized as a seat for receiving the lower portion of the annular depending flange 14 of the rubber cap. More particularly, however, the lower portion of annular flange 14 is closely surrounded by the annular rim 12 and the spaced fingers 23 of the prongs 22 extend upwardly within chamber or recess 15, slightly compressing the inclined annular lip 16 while the tapered terminals 24 of the several prongs penetrate into the walls of the vertical annular chamber and hence cap 11 is anchored by the prongs against rotation between rim 12 and the spaced prongs 22 although seated on wall 20 of the backing.

With the rubber cap 11 mounted on the retaining flange 18, the backing is inserted within the shell and pressed upwardly to force the lower portion of depending flange or skirt 14 to be confined between the prongs 22 and rim 21. Subsequently the terminals 24 are bent towards flange 18 to penetrate into the body of the cap.

Having applied the cap to the shell and the backing to the cap, the shell is pressed inwardly to provide detent 19 to preclude downward displacement of the backing relative to the shell.

The finger cushioning device is adapted to be mounted on a key 25 of a lever arm 26 of a typewriter and detent 19 frictionally cooperates with key 25 to maintain the cushioning device in proper position, it being noted that with the cushioning device mounted on a key, a pneumatic chamber is formed between the cap and the key.

By the present arrangement a positive lock is provided to prevent removal of the cap from the shell. In this connection, it will be observed that the annular flange 18 abuts the vertical face of annular groove 17 while the spaced prongs enter into a portion of flange 14 above groove 17, hence it is apparent that flange 18 and the several prongs cooperate to grip the reduced portion 27 of skirt 14, the action of the

prongs being in opposition to action of flange 18 to compress reduced portion 27 and to preclude reduction of the diameter of groove 17, that is the action of the prongs prevents reduction of the outside diameter of the reduced portion 27, hence the cap is locked to the shell against removal.

Without further analysis, the foregoing disclosure will so fully reveal the gist of the present invention that others can by applying current knowledge readily adapt it for various applications without omitting certain features, that from the standpoint of the prior art, fairly constitute essential characteristics of the generic and specific aspect of the invention and therefore such adaptations should and are intended to be comprehended within the meaning and range of equivalency of the following claims.

I claim:—

20 1. In a finger cushioning device, the combination of, a shell having an annular flange, a resilient indicia identified cap retained by said flange and comprising an annular depending portion, a backing having an annular rim interposed between said shell and depending portion, and a plurality of prongs extending upwardly from said backing and each including a relatively sharp tapered terminal adapted to penetrate the body of said cap to prevent removal 30 of the latter from said flange.

25 2. In a finger cushioning device, the combination of, a shell having an annular flange, a resilient indicia identified cap retained by said flange and comprising an annular depending portion defining a centrally arranged chamber, an anchoring member comprising a backing abutting said depending portion and including an annular rim interposed between said shell and depending portion, said anchoring member having a plurality of prongs extending upwardly 40 into said chamber and including means adapted to enter a part of the body of said cap to prevent removal of the latter from said flange.

30 3. In a finger cushioning device, the combination of, a shell having an annular flange, a resilient indicia identified cap retained by said flange and comprising an annular depending portion defining a centrally arranged chamber, an anchoring member comprising a backing 45 abutting said depending portion and including an annular rim interposed between said shell and depending portion, said depending portion comprising an inclined annular lip, said anchoring member having a plurality of spaced prongs 50 for compressing said lip and including inclined relatively sharp pointed terminals adapted to pierce the body of said cap to prevent rotation of the latter relative to said backing and prevent removal of said cap from said flange.

35 4. In a finger cushioning device, the combination of, a shell having an annular flange, a resilient indicia identified cap retained by said flange and comprising an annular depending portion defining a centrally arranged chamber, 60 an anchoring member comprising a backing abutting said depending portion and including an annular rim interposed between said shell and depending portion, said depending portion comprising an annular lip having an inclined surface disposed at the lower portion of said chamber, said anchoring member having a plurality 65

of spaced upwardly extending prongs extending within said chamber and adapted to compress said lip, each of said prongs including a tapered projection for penetrating the body of said cap above said lip to prevent removal of said cap 5 from said flange.

5. In a finger cushioning device, the combination of, a shell having an annular flange, a resilient indicia identified cap retained by said flange and comprising an annular depending portion defining a centrally arranged chamber, an anchoring member comprising a backing abutting said depending portion and including an annular rim interposed between said shell and said depending portion, said depending portion comprising a lip disposed at the lower portion of said chamber, said anchoring device comprising upwardly extending prongs projecting into said chamber and adapted to abut said lip and including pointed terminals for penetrating the 20 sides of said chamber above said lip and compressing a part of said depending portion against said flange to prevent removal of said cap therefrom.

6. In a finger cushioning device, the combination of, a shell having an annular flange, a resilient cap having an annular depending portion and including an annular groove for receiving said flange to position said cap in respect to said shell, and a backing member comprising means 30 for seating the lower part of said depending portion and including a plurality of spaced upstanding prongs extending within said depending portion, each of said prongs including a tapered projection for penetrating said depending 35 portion above said groove to compress a restricted portion of said cap against said flange to prevent removal of said cap from said shell.

7. In a finger cushioning device, the combination of, a shell having an annular flange, a resilient cap having a depending portion defining a vertically disposed chamber and including a horizontally disposed annular groove receiving said flange and defining a restricted portion between said chamber and groove, and a backing 40 comprising means for retaining the lower part of said depending portion and including a plurality of spaced upstanding prongs abutting the inner surface of said chamber, each of said prongs comprising a tapered and inclined projection for penetrating said depending portion to compress said restricted portion against said flange.

8. In a finger cushioning device, the combination of, a shell having an annular flange, a resilient cap having a depending portion defining a vertically disposed chamber and including a horizontally disposed groove receiving said flange and defining a restricted annular portion between said chamber and groove, and a backing comprising means for retaining the lower part of said depending portion and including spaced upstanding and outwardly inclined prongs adapted to abut the inner surface of said chamber, each of said prongs having an upwardly and outwardly inclined tapered projection for penetrating said depending portion above said groove to compress said restricted portion against said flange to prevent removal of said cap from said shell.

JACK LINSKY.
